(57) CLAIM

The ornamental design for a case for oral care device as shown and described.

DESCRIPTION

FIG. 1 is a perspective view of a case for oral care device from the back, embodying the new design;

FIG. 2 is a perspective view thereof from the front;

FIG. 3 is back view thereof;

FIG. 4 is left side view thereof;

FIG. 5 is a front side view thereof;

FIG. 6 is a right view thereof

FIG. 7 is a top view thereof; and

FIG. 8 is a bottom view thereof.

FIG. 9 is a perspective view of the case for oral care device of FIG. 1 with the top portion removed, embodying the new design;

FIG. 10 is a back view thereof;

FIG. 11 is left view thereof;

FIG. 12 is front side view thereof;

FIG. 13 is a right side view thereof;

FIG. 14 is a top view thereof; and,

FIG. 15 is a bottom view thereof.

In the drawings, the evenly-spaced broken lines depict portions of the case for oral care device that form no part of the claim.

1 Claim, 8 Drawing Sheets
